UNITED STATES PATENT OFFICE.

IRVING CORSER, OF PORTLAND, OREGON.

RELEASING-HOOK FOR LIFE-BOATS.

1,301,392.

Specification of Letters Patent. Patented Apr. 22, 1919.

Application filed July 17, 1918. Serial No. 245,367.

To all whom it may concern:

Be it known that I, IRVING CORSER, a citizen of the United States, residing at Portland, in the county of Multnomah and State 5 of Oregon, have invented certain new and useful Improvements in Releasing-Hooks for Life-Boats, of which the following is a specification.

This invention relates to releasing hooks 10 for life boats and has for its object the provision of means whereby capsizing of the boat as it is launched or in the act of being freed from a ship will be prevented. A further object of the invention is to provide 15 mechanism for the stated purpose which will prevent premature release of the boat and which, when released, will be held in such position until again fully engaged with suspending or raising and lowering devices. 20 Incidental objects of the invention will appear in the course of the following description and the invention resides in certain novel features which are illustrated in the accompanying drawings and particularly 25 pointed out in the claims following the description.

In the drawings—

Figure 1 is a view showing my improved releasing hooks in elevation and in position 30 upon a boat;

Fig. 2 is an enlarged sectional elevation of the releasing hook at the bow of the boat;

Fig. 2^a is a similar view of the hook at the stern of the boat;

Fig. 3 is a plan view of the parts shown 35 in Fig. 2;

Fig. 4 is a section on the line 4—4 of Fig. 2;

Fig. 5 is a section on the line 5—5 of 40 Fig. 1;

Fig. 6 is a detail showing a modification;

Fig. 7 is a sectional elevation showing a further modification.

In carrying out my invention, I secure to 45 the post 1 in the bow of the boat and to the stern post 2, straps or supporting bars 3 which are of counterpart construction, being provided with openings 4' through which suitable securing bolts 4 are inserted to se-

50 cure them to the respective posts and each strap or bar being provided on its inner face near its lower end with a lug 5 and near its upper end with an extended lug 6, as shown.

To the opposite sides of the upper lugs 6, I 55 secure flanges or side plates 7 which extend inwardly and upwardly from the respective

lug and are connected at their upper extremities by a transverse stop pin 8. The upper edges of the flanges or side plates 7 are shaped to provide a concave seat 9 below and leading from the stop 8 and in advance of said seat to provide an upstanding tongue or lug 10. A U-shaped strap or bar 11 is secured to the opposite sides of the lower lug 5 of each supporting bar and constitutes a guide loop projecting inwardly from the said lug to receive the operating lever or dog and thereby prevent lateral movement or twisting of the said lever or dog and also limit the movement of the same 60 away from the supporting bar. It is to be noted that, at both ends of the boat, the upstanding lugs or tongues 10 of the side plates are in advance of the stop extremity 8 of the same side plates and the hooks about to be 65 described are pivoted upon the said lugs and have their rear ends projected toward the said stops so that the hooks at both ends of the boat will open or close in the same direction. At the stern of the boat, obviously, 70 the hook will be pivoted at a greater distance from the supporting bar than the hook at the bow of the boat and the side plates at the stern are, therefore, provided with an additional support in the form of braces or 75 straps 12 which have their lower ends secured to the lug 5 and their upper ends secured to the outer lower corners of the side plates.

The hooks 13 are substantially angle 90 levers pivoted at their bends by pins 14 to and between the upper extremities of the lugs 10 of the side plates and the upper members or bills of the hooks extend approximately horizontally in the closed position and bridge the space between the two 95 horns or branches of the side plates, as shown clearly in Figs. 2 and 2^a, so that the suspending rings 15, when engaged by the hooks, will be held within a grapple free 100 of openings. The lower members or shanks 16 of the hooks extend downwardly approximately vertically in the closed position and the rear or lower edge of the bill of each hook is curved, as shown at 17, so as to 105 meet and merge into the curve 9 of the side plates and thereby provide an opening of approximately circular outline in which the ring or hook 15 of the suspending or raising and lowering chains will be received. In 110 the preferred form, the edge 17 of the hook inclines upwardly from the extremity of

the bill so that the ring 15 will tend to ride up toward the angle or bend of the hook, thereby guarding against accidental disengagement of the ring from the hook. On the 5 rear edge of each shank is a rearwardly extending toe 18 and from the base of the toe the shank depends so as to provide an angular notch 19 to engage the upper forward corner of an operating lever or dog 20. The 10 lower extremity of the shank 16 is given an ogee form, as shown at 21, whereby there is provided an inclined surface to ride upon the upper corner of the dog or lever and to depress the dog. It will be noted that in 15 the particular outline shown in Figs. 2 and 2^a, there is a slightly concave surface to permit the hook to clear the corner of the dog and a convex surface to ride on and depress the dog after the corner of the hook has 20 cleared the corner of the dog. The operating lever or dog is fulcrumed at its upper rear corner upon a pin 22 inserted transversely through the side plates or flanges 7 and is so disposed that its front corner will 25 engage the notch 19 of the hook when the parts are in the closed position. The dog tapers toward its lower end and passes through the loop 11 to extend below the same and terminate below the thwarts. The lower 30 portions of the dogs are provided with a plurality of openings 23 so that a connecting rod 24 may be fitted in the proper opening and be disposed just below the thwarts, the portion of the lever or dog below the connecting bar being then cut away. In this 35 manner the levers or dogs may be all made of maximum length and then fitted to the smallest life boats. The front edge of each dog at the upper extremity thereof is very 40 slightly curved, as shown at 25, so that when the dog is swung rearwardly its upper corner will readily clear the notch 19 while holding the hook in closed position until the corner of the dog has cleared the notch. Im- 45 mediately upon the corner of the dog clearing the notch or the extreme lower rear corner of the hook, the weight of the loaded boat will cause the boat to move downwardly relative to the hooks or rings 15 and said 50 rings by reason of their engagement with the hooks 13 will cause said hooks to swing about their pivots 14, whereupon the boat will be released. As the hooks 13 swing about their pivots, the shanks 16 will move 55 rearwardly and the extreme lower edges of the shanks will ride over the corners of the dogs and prevent the same swinging toward the closed position and exert a downward pressure upon the same which will force 60 them to swing rearwardly in the event they have not been moved to the extreme rearward position. As the dogs are connected by the rod 24, it will be readily noted that the hooks must release simultaneously and the 65 hook at one end of the boat cannot be re-

leased before the hook at the other end is released so that capsizing of the boat will be avoided. The open or released position of the parts is indicated by dotted lines in Figs. 2 and 2^a, and intermediate positions are 70 also indicated in Fig. 2. It will be noted upon reference to said figures that when the dogs are in released position, the hooks may swing freely and, therefore, if an attempt be made to lower the boat before the dogs are 75 returned to closed position the hooks will immediately swing into open position and release themselves from the davit chains so that the boat cannot be lowered unless the hooks are locked. 80

In connecting the levers or dogs 20, when applying the device to a boat, the dogs are swung forwardly to their extreme or locked position. The rod 24 is then pivotally connected at its rear end to the lower end of 85 the rear dog by means of a fork 26 and a pivot pin 27 inserted through the said fork and one of the openings 23. The opposite end of the rod 24 is tubular to receive the threaded stem 28 of a fork 29 which is piv- 90 oted by a pin 30 to the forward lever or dog. An adjusting nut 31 and a lock nut 32 are mounted upon the stem 28 to engage the front end of the rod 24 and adjustably connect the same with the stem 28 so that the 95 dogs will be fixed in relation to each other and obliged to move simultaneously and in the same direction when the connecting rod is operated. A guide 52 is preferably pro- 100 vided for the rod 24 on the under side of a thwart 33 and brackets 34 are also provided adjacent the said rod. A handle 35 is loosely fitted upon the rod between pins or other form of stops 36 so that while the handle may be swung about the rod it can- 105 not move longitudinally of the same. When the mechanism is in the locked or closed position, the handle 35 will bear against the front side of the forward bracket 34 and will, consequently, prevent rearward 110 movement of the parts, said bracket being provided with a lug 53 to bear against the handle and preventing it swinging against an occupant of the boat. When it is neces- 115 sary to release the hooks, the handle is swung upwardly so as to clear the adjacent bracket 34 and is then moved rearwardly, the rod 24 following the latter movement so that the dogs will be released from the 120 hooks and the hooks, consequently, permitted to open. The handle upon being released will engage against the rear side of the rear bracket 34 and will, consequently, prevent forward movement of the dogs un- 125 til manually released after the hooks have been again engaged in suspending devices. 130

In Fig. 6, I have shown a slightly different form of the invention in which the lower extremity of the hook is straight, as shown at 37, while an ogee surface 38 is formed

on the upper edge of the dog. This formation or reversal of the form shown in the previously described arrangement will operate in the same manner and it may sometimes be preferred.

In Fig. 7, I have shown a further modification in which the dog is replaced by a lever 39 pivoted intermediate its ends to the side plates as at 40 and having its front end of the same shape as the upper front corner of the dog shown in Fig. 6. A lug 41 is provided on the under edge of the lever 39 at the front end thereof and a link 42 is pivoted at its upper end to this lug on the 10 lever at the stern of the boat. The corresponding link at the bow of the boat is pivoted to the rear end of the lever, as shown, and the lower ends of both links are pivoted to the inner corners of bell-crank levers 43 which are pivoted at their upper rear corners to the lower lugs 44 on the supporting bars or straps, an operating rod 45 connecting the lower ends of said angle levers, as shown, in the same manner as the connecting 20 rod 24 operates as previously described.

It will be readily seen from the foregoing description, taken in connection with the accompanying drawings, that I have provided a very simple and efficient mechanism 30 whereby a life boat may be quickly released when upon an even keel and by which the release of one end of the boat prior to the release of the other end thereof is prevented. As the releasing hooks at both ends of the 35 boat move in the same direction they can be operated simultaneously by a single actuating member and the construction of the engaging parts is such that should one hook tend to open slightly ahead of the other 40 hook, the hook so tending to open will bear upon and depress the coacting dog, the movement of said dog being imparted to the operating rod and thereby causing the dog at the opposite end of the boat to move to 45 released position. My improved mechanism may be readily applied to any life boat and will not take up valuable space therein, although it will be so disposed that it may be easily reached by the officer in charge and 50 manipulated. When the parts are in closed position, they are positively locked against release by the engagement of the dogs with the hooks and will remain so locked until the dogs are oscillated. When the dogs are 55 moved about their pivots, the hooks will remain closed until the corners of the dogs clear the corners of the hooks whereupon the lower extremities of the hooks will ride upon the dogs and exert a cam action thereon to 60 depress the same. The movement of either dog will be transmitted, as described, to the other dog so that the two ends of the boat will be released simultaneously notwithstanding some inaccuracy in the adjustment 65 of the operating rod. The particular out-

line of the hook may be varied as may be desired provided there is such relation between the hook and the dog that immediately upon the upper end of the dog being swung from behind the hook, the lower end 70 of the hook will ride upon and depress the dog. When the hook is in fully open position, the toe 18 forms a guide and abutment against which the suspending ring may be engaged and pressed to effect return of the 75 hook to closed position in engagement with the ring, and the end of the hook, by engaging the stop 8, as shown in dotted lines in Fig. 2, supports the hook in the open position. 80

Having thus described the invention, what is claimed as new is:

1. The combination of fore and aft supports, hooks mounted in said supports and having shanks provided with notches in 85 their lower portions and cams adjacent said notches, dogs mounted on the supports below and in rear of the hooks and having their upper front corners arranged to engage said notches, the cam portions of the hooks being 90 adapted to ride on the upper front corners of the dogs after the same have cleared said notches, and means for moving the dogs to cause their upper front corners to clear the notches. 95

2. The combination of fore and aft supports, each comprising spaced side plates having upstanding portions and lugs in advance of and spaced from said portions, hooks pivoted to said lugs and having their 100 bills arranged to coöperate with the upstanding portions of the side plates and having notches in their lower ends, dogs pivoted upon the side plates in rear of the hooks and having their upper forward corners arranged to engage said notches, and an operating member connecting the lower ends of the dogs. 105

3. The combination of supporting plates, hooks pivoted on said plates and having 110 their bills arranged to coöperate therewith, dogs pivoted on the plates and having their upper front corners arranged to engage the shanks of the hooks, the shanks of the hooks having eccentric extremities arranged to 115 ride on the upper ends of the dogs and depress the same as the dogs are moved to open position, and means for simultaneously operating said dogs.

4. The combination of fore and aft supports, hooks pivotally mounted in said supports and bearing against the same in closed position, dogs pivoted upon the supports in rear of the hooks and having their upper front corners arranged to engage the hooks, 125 guides projecting from the supports and passing around the dogs, and an operating rod connecting the lower ends of the dogs.

5. The combination of supports, hooks pivotally mounted upon the supports, dogs 130

5 pivoted upon the supports below and in rear of the hooks and arranged to engage the hooks and hold them in closed position, a connecting rod having one end attached to the lower end of one dog, an adjustable connection between the opposite end of said rod and the lower end of the other dog, stops adjacent said rod, and a handle mounted upon the rod for rotation about the same but restrained from longitudinal movement thereon and adapted to engage against one of said stops.

10 6. In a mechanism for the purpose set forth, the combination of a side plate having an upstanding stop member and an upstanding lug in advance of and spaced from said stop member, the intervening edge of the plate being indented, a hook pivoted upon the said lug and having its bill disposed to 15 bridge the space between the said lug and said stop member, the under edge of said bill being shaped to merge into the indented portion of the edge of the plate and the shank of the hook being constructed with a 20 notch at its lower rear corner, a dog pivoted upon the plate below and in rear of the hook and having its upper forward corner arranged to normally engage said notch, and means for swinging the dog to cause its 25 upper forward corner to clear the notch.

30 7. The combination of a supporting plate

35 having a stop member at its upper end and a lug in advance of and spaced from said stop member, the intervening edge of the plate being indented, a hook pivoted upon said lug and having a rearwardly extending bill adapted to bear against the stop member, the under edge of the bill merging into the indented portion of the edge of the plate and the shank of the hook having an angular notch at its lower rear corner and having a curved edge at its lower extremity, a dog pivoted upon the plate in rear of and below the hook and having its upper forward corner arranged to engage said notch, 40 the forward edge of the dog at the upper extremity thereof being cut away to permit the dog to be disengaged from said notch while still holding the hook in closed position, and means for operating said dog.

45 8. The combination of a support, a hook pivoted thereon and co-operating therewith to retain a suspending device, and a dog pivoted upon the support and normally engaging the hook to hold the same in closed 50 position, the hook being provided with an eccentric portion arranged to ride on and depress the dog when the latter is moved toward released position.

55 In testimony whereof I affix my signature.

IRVING CORSER. [L. s.]
